UNITED STATES PATENT OFFICE.

WILLIAM FRANK KASBOHM, OF VAN WERT, OHIO.

WINDOW-SHADE AND CURTAIN-POLE BRACKET.

1,341,562.

Specification of Letters Patent.

Patented May 25, 1920.

Application filed November 26, 1919. Serial No. 340,753.

To all whom it may concern:

Be it known that I, WILLIAM FRANK KASBOHM, a citizen of the United States, residing at Van Wert, in the county of Van Wert and State of Ohio, have invented certain new and useful Improvements in Window-Shade and Curtain-Pole Brackets; and I do hereby declare the following to be a full, clear, and exact description of the invention, 5 such as will enable others skilled in the art to which it appertains to make and use the same.

This invention relates to an improved bracket for supporting a window shade and 15 curtain pole. One object of the invention is to provide a bracket so constructed that it may be adjustably mounted and further to construct the bracket so that it may be releasably but securely held in an adjusted 20 position.

Another object of the invention is to construct this bracket so that it may be formed of sheet metal cut the proper length and bent into the proper shape.

25 Another object of the invention is to construct this bracket so that it may be cheaply produced and to further construct it so that it may be easily and quickly put in place.

This invention is illustrated in the accompanying drawings wherein:

Figure 1 is a view showing the curtain bracket in front elevation.

Fig. 2 is a side elevation of the improved bracket.

35 Fig. 3 is a perspective view of the supporting strip with which the bracket is adjustably connected.

This device comprises a bracket indicated in general by the numeral 10 and a support 40 indicated in general by the numeral 11. The support 11 is formed from a strip of metal cut the proper length and having its end portions bent to provide attaching feet 12 having openings 13 formed therein to receive 45 the fastener screws 14. This support will be put in place and will extend transversely of the window casing, one of the supports being positioned at each side of the casing near the upper end.

50 The bracket 10 is also formed from a strip of sheet metal which is bent intermediate its length to provide the standard or upright arm 15 having an upper arm 16 extending from its upper end and a bracing arm 17 55 extending upwardly from its lower end in diverging relation to the standard and con-

nected with the upper arm 16 by a rivet 18 which passes through the arm 16 and through a foot 19 formed by bending the free end portion of the bracing arm 17. 60 The free end portion of the upper arm 16 extends beyond the upper end of the bracing arm and is bent to provide a socket 20 in which the curtain pole will rest, a set screw 21 being provided and extending through 65 the free end of the strip to engage the curtain pole and to retain the pole in the socket or seat 20. A cross strip 22 extends from the standard 15 at a point above the seat 23 and is connected with the standard 15 and 70 with the bracing arm 17. This cross strip 22 serves to brace the bracing arm 15 and is provided with a notch or cut out 24 providing a socket to receive the pintle of a curtain roller. It will thus be seen that when 75 the curtain brackets are in place with one mounted upon each side of the upper portion of the window casing a curtain pole and a curtain roller may be supported by the two brackets. In order to releasably and 80 adjustably connect the brackets with the supporting strip 11 there has been provided a securing bolt 25 which extends through a slot 26 formed in the strip 11 and also extends through an opening formed in the 85 standard 15 at the seat 23. If desired a block 27 may be placed upon the bolt thus providing efficient means for engaging the inner face of the strip 11 when the securing nut 28 is tightened to secure the brackets in 90 a set position. By loosening the nut the brackets will be moved along the strip to a desired position and then again secured by tightening of the nut. It has therefore been provided a curtain pole and shade roller 95 support so constructed that it may be easily put in place and further so constructed that the bracket portion thereof may be securely but releasably held in an adjusted position for proper engagement with the pintle of a 100 shade roller.

What is claimed is:—

1. A device of the character described comprising a supporting strip provided with a longitudinally extending slot and having 105 its end portions bent to provide attaching feet having fastener receiving openings, a bracket formed of a strip bent to provide a standard having upper and lower arms extending therefrom, the lower arm being carried upwardly in diverging relation to the standard and connected to the upper arm to 110

brace the upper arm, the upper arm having its free end portion bent to provide a pole receiving seat positioned beyond the outer end of the lower arm, a cross strip extending between and connected with the standard and bracing arm and provided intermediate its ends with a cut out for receiving a pintle of a curtain roller, and a fastener passing through the slot of the supporting strip and through said standard to releasably hold the bracket in an adjusted position on the supporting strip.

2. A device of the character described comprising a supporting strip provided with a longitudinally extending slot, a bracket having a standard bent intermediate its length to provide a seat for receiving said supporting strip, a fastener passing through

the slot of said strip and through said standard, a block carried by said fastener for engaging the inner face of the strip when the fastener is tight to releasably hold the bracket in a set position, an upper arm extending from the standard and terminating in a pole receiving seat, the bracing arm extending from the lower end of the standard and connected with the upper arm, and a strengthening strip positioned between the bracing arm and the standard having a pintle receiving seat.

In testimony whereof I affix my signature in presence of two witnesses.

WILLIAM FRANK KASBOHM.
